United States Patent

Des. 235,457
Patented June 17, 1975

235,457

LIGHTER

Masaaki Takashima, 12-10, 2-chome, Mejiro,
Toshima-ku, Tokyo, Japan

Filed Apr. 18, 1974, Ser. No. 461,850

Claims priority, application Japan Oct. 23, 1973

Term of patent 14 years

Int. Cl. D27—05

U.S. Cl. D27—42

FIG. 1

FIG. 2

FIG. 3

FIG. 4

FIG. 5

FIG. 6

FIG. 1 is a perspective front view of a lighter showing my design;

FIG. 2 is a view similar to FIG. 1, but viewing from the bottom of the lighter;

FIG. 3 is a front elevational view of the lighter;

FIG. 4 is a right side elevational view thereof;

FIG. 5 is a top plan view thereof; and

FIG. 6 is a bottom plan view thereof.

I claim:

The ornamental design for a lighter, as shown.
